HAIR DRYER

Dieter Rams, Koenigstein, Taunus, Germany, assignor to Braun Aktiengesellschaft, Frankfurt am Main, Germany, a firm

Filed July 7, 1969, Ser. No. 18,085

Claims priority, application Germany Jan. 29, 1969

Term of patent 14 years

Int. Cl. D3—03

U.S. Cl. D86—10

FIG. 1

FIG. 4

FIG. 1 is a front perspective view of a hair dryer showing my new design, the side opposite being reversely similar;

FIG. 2 is a front perspective view taken from the left of FIG. 1;

FIG. 3 is a bottom perspective view; and
FIG. 4 is a top plan view.

I claim:

The ornamental design for a hair dryer, substantially as shown and described.
